UNITED STATES PATENT OFFICE.

MARCELLUS HARWOOD YOUNG AND JAMES M. MATHEWS, OF SEATTLE,
WASHINGTON; SAID MATHEWS ASSIGNOR TO SAID YOUNG.

EXTENSION-TABLE.

SPECIFICATION forming part of Letters Patent No. 521,905, dated June 26, 1894.

Application filed August 3, 1893. Serial No. 482,282. (No model.)

To all whom it may concern:

Be it known that we, MARCELLUS HARWOOD YOUNG and JAMES M. MATHEWS, citizens of the United States, residing at Seattle, in the 5 county of King and State of Washington, have invented certain new and useful Improvements in Extension-Tables; and we do hereby declare the following to be a full, clear, and exact description of the invention, such as will 10 enable others skilled in the art to which it appertains to make and use the same, reference being had to the accompanying drawings, in which—

Figure 1 is a perspective view of the table, 15 with the drop leaves folded. Fig. 2 is a like view with the table partially extended. Fig. 3 is a like view with the frame open to the fullest extent. Fig. 4 is a bottom view of the table top; Fig. 5 a top view and Fig. 6 an end 20 view of the table, and Fig. 7 a top view of the table frame folded.

Like letters indicate corresponding parts.

The object of our invention is to provide an extension table simple in construction, 25 convenient in use, and capable of being extended to great length or folded within a very small space.

Our invention consists in certain devices and combinations hereinafter described.

30 E are the end-bars of a table-frame. F are the side-bars thereof, each in four sections united at H by means of hinges, allowing them to be folded as in Fig. 2. It will be observed that the extension folds of F may extend 35 entirely across the frame, making the folding capacity very great; also that, to make this possible, the alternate end sections of F (fixed to the table legs) are of different lengths.

When the frame is extended (Fig. 3) it is 40 kept in position by means of a detachable bar at I placed between the folding bars F, or by means of hooks or other suitable devices at C.

B are leaves of the table which rest upon the frame, whether folded or extended; but 45 are movable, when the frame is extended, along the bars F.

A are drop-leaves, hinged to B at G.

On the under side of B and near each end thereof, are short cross-bars D, made of wood 50 or metal, and having a projection on the side

next the table-frame, designed to fit loosely in corresponding grooves on the outer side of F as shown in Fig. 6. The grooves extend the entire length of the side pieces F and where the legs extend beyond the ends of the side pieces, as shown in Figs. 1, 2, 3, and 6, the groove may be continued through the upper portion of the outside of the leg. It will therefore be seen that the leaves B cannot be removed therefrom when the table is either 55 folded or entirely extended; but they can be easily removed when the frame is only partially folded, by raising the drop-leaves, and moving B in the direction of the center of the table, thus detaching the bars D from the 60 grooves in F.

The legs of the table may be made in two sections, united by means of a screw-joint at O (Fig. 6). By detaching the table-top, as already explained, and the lower portion of 70 the legs the entire table may be put into the most compact and the safest form for shipment.

S and S' are bars fixed on the under side of B and A, which bars, striking against E, regulate the distance to which A and B may be moved along F in either direction.

At P is a dowel pin in E near the upper edge thereof, designed to fit in an opening in S' when the table is extended (Fig. 6) and 80 hold the leaf A in place.

L are cross-bars fixed on the under side of the leaves A, designed to strengthen A and, by passing in cross-grooves in the upper edge of E, Fig. 6 to guide the movement of the 85 leaves when opening or closing the table.

At T (Fig. 7) are hooks or other suitable devices for fastening the frame together when folded.

To extend the table, detach the fastening 90 at T, unfold the frame, attach the fastening C or I (Fig. 3), raise the drop-leaves A and slide them along F until the stops S' strike against E, or until the leaves B meet in the center of the table.

Figs. 2 and 7 show that the smallness of the space within which the table may be folded is practically limited only by the thickness of the bars E and F and of the legs, and by the width of the leaves B. Folded into 95 100

this narrow space it can be easily removed from the room occupied by it, or placed in a niche or receptacle made for that purpose. It may thus be used in connection with a side-board, the lower portion of which is made to receive and inclose the table.

The length of the table when extended as hereinbefore described, will be the combined width of the leaves A and B. But, as shown 10 in Fig. 5, a further extension may be made by inserting extra leaves X between the leaves B, and it may be still further extended in 15 length by separating the leaves B to the farthest extent (Fig. 3) filling the space between them with auxiliary leaves, and supporting the drop leaves A by means of auxiliary detachable legs attached at Y (Fig. 4) to the under side of A by a screw-joint or other desirable device. Thus the table may, without 20 the extra legs and leaves, be sufficiently extended for all ordinary use, while the combination of the folding frame, the sliding top and the auxiliary leaves and legs, makes the extremes within which the table may be extended or folded very great.

If it is not desired to extend the table to full length, it may, after being folded (Fig. 1) be partially extended by raising only one of the leaves A and supporting it by means of 30 an auxiliary leg Y.

We are aware that tables have been made with folding bars the folding sections of which extend but half the distance across the frame, and requiring twice the number of folds to 35 make the same extension as ours; also that an extension table having drop-leaves, supported by auxiliary legs is not new; also that a table having a portion of its top movable in connection with movable legs is not new. 40 These constructions we do not claim, but Having thus described our invention, what

we claim as new therein, and desire to secure by Letters Patent, is—

1. An extension table consisting of a folding frame, having the end bars, E, the folding bars F, divided and hinged as hereinbefore set forth; the movable detachable top consisting of the leaves B and A, having the bars D and L and the stops S and S'; the auxiliary leaves X; and auxiliary detachable legs 50 Y all arranged substantially as and for the purposes specified.

2. The movable top consisting of the leaves B, attached to the table-frame by means of the bars D, the drop-leaves A, and the auxiliary leaves X, all constructed and arranged to operate as set forth.

3. The combination in an extension table of the folding frame having the bars F consisting of the long extension folds and the alternate long and short end sections, and the legs, detachable at O; the sliding top consisting of the leaves B and A with bars D and L and stops S and S', the extra leaves X, and the auxiliary legs Y, all arranged substantially 65 as and for the purposes specified.

4. In an extension table, the combination of the folding frame with the sliding top consisting of the leaves B, attached to the frame by means of the bars D, and the drop leaves 70 A attached to B by means of hinges at G having the guide bars L, and held in place by means of the stop S' fitting over a pin P, all constructed and arranged substantially as and for the purposes set forth.

In testimony whereof we affix our signatures in presence of two witnesses.

M. HARWOOD YOUNG.
JAMES M. MATHEWS.
